UNITED STATES PATENT OFFICE.

ELLIOTT W. BRÜCKNER, OF JERSEY CITY, NEW JERSEY.

DESIGN FOR A DOLL.

Application filed January 28, 1926. Serial No. 16,314. Term of patent 7 years.

To all whom it may concern:

Be it known that I, ELLIOTT W. BRÜCKNER, a citizen of the United States, residing at Jersey City, in the county of Hudson and State of New Jersey, have invented a new, original, and ornamental Design for Dolls, of which the following is a specification, reference being had to the accompanying drawing, forming part thereof.

I claim:

The ornamental design for a doll, as shown.

ELLIOTT W. BRÜCKNER.
